CAMERA ACCESSORIES BRACKET

Norman D. Schroth, 1705 E. Wood, Decatur, Ill.

Filed Dec. 7, 1964, Ser. No. 82,924

Term of patent 14 years

(Cl. D61—1)

I claim:

The ornamental design for a camera accessories bracket, as shown and described.
